CLAIM

The ornamental design for a limousine console for bar accessories and the like, as shown and described.

DESCRIPTION

FIG. 1 is a perspective view of a limousine console for bar accessories and the like showing my new design;

FIG. 2 is a top plan view thereof;

FIG. 3 is a front elevational view thereof;

FIG. 4 is a right side elevational view thereof, the opposite side elevational view being a mirror image of FIG. 4;

FIG. 5 is a rear elevational view thereof; and

FIG. 6 is a bottom plan view thereof.

FIG.1
